CLAIM

The ornamental design for a power pack as shown and described.

DESCRIPTION

FIG. 1 is a top, front perspective view of a first embodiment of a power pack showing our new design.

FIG. 2 is a bottom rear perspective view of the power pack of FIG. 1.

FIG. 3 is a front view of the power pack of FIG. 1.

FIG. 4 is a back view of the power pack of FIG. 1.

FIG. 5 is a right side view of the power pack of FIG. 1.

FIG. 6 is a left side view of the power pack of FIG. 1.

FIG. 7 is a top view of the power pack of FIG. 1.

FIG. 8 is a bottom view of the power pack of FIG. 1.

FIG. 9 is a top, front perspective view of a second embodiment of a power pack showing our new design.

FIG. 10 is a bottom rear perspective view of the power pack of FIG. 9.

FIG. 11 is a front view of the power pack of FIG. 9.

FIG. 12 is a back view of the power pack of FIG. 9.

FIG. 13 is a right side view of the power pack of FIG. 9.

FIG. 14 is a left side view of the power pack of FIG. 9.

FIG. 15 is a top view of the power pack of FIG. 9.

FIG. 16 is a bottom view of the power pack of FIG. 9.

FIG. 17 is a top, front perspective view of a third embodiment of a power pack showing our new design.

FIG. 18 is a bottom rear perspective view of the power pack of FIG. 17.

FIG. 19 is a front view of the power pack of FIG. 17.

FIG. 20 is a back view of the power pack of FIG. 17.

FIG. 21 is a right side view of the power pack of FIG. 17.

FIG. 22 is a left side view of the power pack of FIG. 17.

FIG. 23 is a top view of the power pack of FIG. 17.

FIG. 24 is a bottom view of the power pack of FIG. 17.

FIG. 25 is a top, front perspective view of a fourth embodiment of a power pack showing our new design.

FIG. 26 is a bottom rear perspective view of the power pack of FIG. 25.

FIG. 27 is a front view of the power pack of FIG. 25.

FIG. 28 is a back view of the power pack of FIG. 25.

FIG. 29 is a right side view of the power pack of FIG. 25.

FIG. 30 is a left side view of the power pack of FIG. 25.

FIG. 31 is a top view of the power pack of FIG. 25; and,

FIG. 32 is a bottom view of the power pack of FIG. 25.

The broken lines in the figures show features of the power packs that form no part of the claimed design.
